UNITED STATES PATENT OFFICE.

CHESTERFIELD WHITE, OF ST. LOUIS, MISSOURI, ASSIGNOR TO THE EMERSON ELECTRIC MFG. CO., OF ST. LOUIS, MISSOURI, A CORPORATION OF MISSOURI.

PACKING CASE.

Application filed May 16, 1927. Serial No. 191,628.

This invention relates to improvements in packing cases, and consists in the novel construction and arrangement of parts herein-after disclosed.

5 An object of the invention is to provide a packing case or carton whereby relatively heavy articles may be packed in a fiber board container having provision for preventing the collapse of the side walls of the outer case 10 and for centering the contained article in such a manner that the weight will be distributed, thereby preventing crushing of the container.

Additional advantages of the construction 15 will be apparent from the following detailed description thereof, taken in connection with the accompanying drawing, in which

Fig. 1 is a perspective view of the closed packing case.

20 Fig. 2 is a vertical sectional view.

Fig. 3 is a view of the article supporting frame.

In the embodiment of the invention illustrated in the drawing, the construction is 25 shown as incorporated in a fiber container having connected side walls 1 and a double fold flap top and bottom 2. It will be understood that the outer container is of the usual type used as a packing case and preferably is 30 made of relatively thick fiber board, and that the flaps are integrally connected with the extremities of the side walls and fold in transverse directions across the top and bottom of the case, the top and bottom of the case being 35 secured in any suitable manner.

The article to be packed (in the illustrated embodiment, a fan) is connected to an inserted base member 3, preferably of relatively stiff fiber board. The connection is effected by bolting the base of the fan 4 directly to the member 3 by bolts 5. The connection between the base of the fan and the member 3 centers the packed article in the case. After the connection has been made,

45 the member 3 is inserted in the case with the packed article and a rectangular reinforcing member 6 is inserted against the inner face of the side walls of the outer container, the lower edges of the member 6 being supported 50 on the marginal edge of the member 3.

The member 6 is preferably made of double corrugated board and is so formed that it is readily insertable and removable from the outer container and is of a height so that it 55 extends upwardly in the container a suitable

distance to support on its upper edge a frame or cradle 7. The frame or cradle 7 comprises side members, preferably of wood or other strong rigid material, and is of a dimension so that, when inserted in the outer container, 60 it will lie close against the side walls thereof.

The cradle 7 has a cross member 8. This cross member, as illustrated in Fig. 3 of the drawing, is cut to fit over the upper part of the motor housing and, in the case of a fan provided with a handle attached to the motor housing, is grooved to receive the handle, thereby providing a rigid support between the cradle and the packed article. It is noted, by reference to Fig. 3, that in the under face 70 of the cross member there is a notch 9 and a groove 10. In order to prevent scarring of the packed article, a piece of cloth or other material 11 is first placed over the motor housing and the handle attached thereto, and the frame or cradle 7 is fitted down closely over the upper portion of the motor housing, the outer edge of the frame 7 resting upon the upper edge of the member 6. The cradle or frame 7 thus constitutes a support for the 80 packed article and also constitute a reinforcement for the side walls of the outer case. The packed article is thus centered and held rigidly within the container and out of contact with the side walls. It is prevented from lateral or vertical displacement, for the reason that the frame is held in adjustment by the member 6 and by a rectangular member 12 that fits over the frame or cradle 7 and fills the space between the cradle and the 90 top of the container. The member 12, like the member 6, is preferably formed of double corrugated board and acts as a retaining means for the frame or cradle 7 and, at the same time, reinforces the side walls of the 95 outer case. If desired, a flat sheet 13 of fiber board may be inserted over the upper edge of the member 12 under the flaps of the outer container.

From the foregoing description, it will be 100 understood that a packing case of relatively cheap construction is provided, which is very strong and easily assembled. The members 6 and 12 transmit the weight from the supporting frame or cradle 7 to the inside corners of the case and prevent vertical displacement of the frame or cradle, and thereby vertical displacement of the packed article.

While the construction is described in con- 110

nection with packing portable fans, it will be understood that, by slight modification, it would be useful for the packing of many articles of a similar nature. I do not restrict myself to the exact construction shown and described, therefore, but what I claim and desire to secure by Letters Patent is:—

1. The combination with a container, of a base member adapted to be connected with the packed article, a frame constituting a support for another part of the article spaced a substantial distance below the top of the container, and reinforcing insert rectangular members fitting against the side walls of the container and filling the space between the top and bottom of the container and the frame to hold the frame in position and to distribute the weight imposed thereon by the packed article.
2. The combination with a container of fiber board having side walls and top and bottom members, of a member inserted in said container adjacent to the bottom thereof for supporting the packed article, a wooden frame insertable in said container and having means for connecting it with the packed article, and reinforcing members disposed against opposite side walls of the container for holding the frame in said container at a position substantially spaced from the top and bottom walls thereof.
3. The combination with a container of fiber board having side walls and end members, of a member inserted in said container for supporting one end of the packed article, a wooden frame insertable in said container and having means for connecting it with the packed article, and reinforcing

members of corrugated board fitting against the side walls of the container for holding the frame in adjustment in said container at a position substantially spaced from the top and bottom walls thereof.

4. The combination with a container, of an insertable base member in said container for supporting an article, of an insertable frame in said container adaptable to position the article, and of insertable reinforcing members for positioning and supporting the base member and frame in the container, said reinforcing members being arranged adjacent to opposite side walls of the container above and below the frame, whereby said base member is held in spaced relationship to said frame and said frame spaced a substantial distance from the top of the container.

5. A packing case comprising a container, a base member supported by the bottom wall of the container adapted to support the packed article contained in the case, spacing members positioned against the side walls of the container and having their lower edges bearing against the base member, a relatively rigid frame constituting a support for the upper part of the packed article, said frame being adapted to be inserted in the container and having its lower edge resting upon said spacing members, and a second pair of spacing members positioned against the side walls of the container having their lower edges resting on the frame member and their upper edges extending to the top of the container.

CHESTERFIELD WHITE.
